Fig. 2

Fig. 3

A technical line drawing showing a screwdriver with a wooden handle (14) and a metal tip (15) being used to tighten a screw (16) into a curved metal bracket (20). The bracket has several slots and a central rib. The screw is partially inserted into one of the slots. The screwdriver is shown from a top-down perspective, with the handle pointing upwards and the tip pointing downwards into the screw head.

UNITED STATES PATENT OFFICE

WILLIAM E. DUNNING, OF ALLIANCE, OHIO, ASSIGNOR TO THE McCASKEY REGISTER COMPANY, OF ALLIANCE, OHIO, A CORPORATION OF OHIO

INDEX FOR FILING APPLIANCES

Application filed May 8, 1928. Serial No. 276,070.

The invention relates to indexes such as are used in filing or finding appliances.

Indexes of this kind now in common use usually comprise a leaf of sheet metal or the like having a plurality of spaced parallel ribs formed by wires or the like connected to the face of the leaf forming narrow compartments to receive strips of cardboard bearing the names of the various accounts carried 10 in the filing appliance or register.

These cards are arranged in alphabetical order upon the index leaf and it is, of course, necessary from time to time to add new cards to the index as new accounts are placed in 15 the filing appliance.

These new index cards must be placed in alphabetical position upon the index leaf, and this frequently necessitates changing the position of a great many of the index cards 20 in order to add one new one to the index.

The object of the present improvement is to provide an index which is flexible and by means of which a new index card may be quickly and easily placed in the proper position upon the index leaf with the movement and repositioning of a minimum number of 25 cards.

The above and other objects may be attained by providing a plurality of channel 30 strips upon the index leaf corresponding in number and position to the columns of the index; a plurality of card holders being mounted in said channels, each carrying a card or strip bearing the name of an account 35 in the filing appliance.

These card holders are slidably mounted upon the channel strips and are easily and quickly removable or replaceable thereon, 40 providing a very flexible index which may be readily changed to add new accounts.

An embodiment of the invention is illustrated in the accompanying drawings, in which—

45 Figure 1 is a front elevation of the improved index leaf;

Fig. 2, an enlarged fragmentary horizontal section through a portion of the leaf;

50 Fig. 3, a similar vertical sectional view thereof;

Fig. 4, an enlarged perspective view of one of the card holders;

Fig. 5, a portion of one of the perforated strips of cards;

Fig. 6, a detached elevation of one of the 55 cards;

Fig. 7, a perspective view of the tool by means of which the card holders may be removed and replaced; and

Fig. 8, a front elevation of the tool showing 60 a card holder gripped therein.

Similar numerals refer to similar parts throughout the drawings.

The index leaf may be provided with the frame 1 within which is mounted a plurality 65 of channel strips 2, each having the channel portion 3 at each vertical edge.

These channel strips correspond in number and position to the columns of the index, and in order to provide for a double faced index leaf, the channel strips may be located back to back as best shown in Fig. 2 and spot welded or otherwise attached together. 70

Each of the card holders for the index may comprise a flexible strip of spring steel or the like indicated at 4 of a length sufficient to extend across one of the channel strips and to be engaged beneath the opposite channels 3 thereof. 75

Each of these card holders may be provided at each side of its vertical center, and at points spaced from its ends, with the card retaining flanges 5. These flanges are preferably substantially half-round in cross section, being curved inward over the front face 80 of the strip 4 in order to retain the cardboard strip 6 upon which the name of the account may be written or printed.

These cardboard strips or cards are preferably provided with the serrated edges 7 for 90 the purpose of firmly holding the cards in place within the holders.

As shown in Fig. 5, these cards or strips preferably come in sheets perforated as shown at 8 to form the serrated edges 7 when 95 the cards are torn apart.

The card retaining flanges 5 upon the card holder may be formed of strips 9 of sheet metal having a channel shape in cross section, as well shown in Fig. 3, and each channel 100

strip extends and is clamped around the end portions of the spring member 4 as shown in the drawings.

As shown in Fig. 1, the card holders are arranged in columns, located upon the channel strips 2, the ends of the card holders being engaged in the channels 3 at the sides of said strips.

The cards 6 are placed in the card holders in the manner above described and the names of the various accounts are written or printed upon the cards in alphabetical order as shown. The letters of the alphabet are preferably printed upon certain cards to alphabetically divide the various sections of the index.

When it is necessary to add a new name to the index, the same can be accomplished with a minimum of time and labor. Assuming, for instance, that an account is opened by a party named Bryan, it will be seen that all of the card holders reserved for accounts beginning with "B" are filled.

Glancing over the index, it is seen that the first unused card holder is at the end of the accounts beginning with "G" as indicated at 10. In order to properly place the new card in the index, the empty card holder 10 is removed and a card placed therein with the name Bryan thereon.

The lowermost card holder 11 in the second column from the left is then removed and placed at the top of the third column, the other card holders above the one bearing the letter "H" having slidably moved down the distance of one holder when the card holder 10 was removed.

By removing the lowermost card holder 11 from the second column all of the holders in this column will move downward in the same manner. The lowermost card holder 12 in the first column is then removed and placed in the space at the top of the second column and all of the card holders above the one bearing the letter "C" in the first column may be held in their present position while the holder 10 with the name Bryan thereon is inserted in the space thus provided between the card holder bearing the name F. M. Brown and the one bearing the letter "C".

The flexibility and ease of operation of this index will be appreciated when it is remembered that with the ordinary form of index now in common use, it would have been necessary to remove every card between the one bearing the name F. M. Brown in the first column and the card bearing the letter "H" in the third column.

Each of these cards would then have to be replaced in the next compartment in order to complete the change.

For the purpose of facilitating the removing and replacing of the card holders, the tool shown in Figs. 7 and 8 may be provided.

This tool may be provided with the angu-

larly disposed handle 14 to which is connected the shank 15 having the reduced flattened end 16 adapted to be inserted beneath the central portion of the card holder to be picked up thereby. The bifurcated arms 17 are pivotally connected to the shank 15 as at 18 and provided with the rearwardly disposed operating lever 19.

These arms are provided with the depending end portions 20 for engagement with the top or front surface of the card holder near opposite ends, and a spring 21 may be provided for normally holding the parts in the positions shown in Fig. 7.

In order to remove a card holder from the index, the reduced end 16 of the shank is inserted beneath the central portion of the card holder and the lever 19 and handle 14 are pressed toward each other, moving the bifurcated arms 17 downward into contact with the surface of the card holder near its ends, and raising the shank 15, flexing the card holder in the manner shown in Fig. 8.

The end portions of the card holder are thus drawn out of engagement with the channels 3 of the channel strip, permitting the holder to be removed.

When a card holder is to be inserted in the index, it is placed in the tool in the position shown in Fig. 8, and then moved to the desired position in the index when the lever 19 may be slowly released, permitting the spring 21 to move the parts back to the normal position.

With this operation of the tool, the card holder resumes its normal straight or flat position, the ends thereof being engaged in the channel portions 3. The tool may then be removed without disturbing the card holder.

It will be obvious from the above description and the accompanying drawings that an index is provided which may be quickly and easily changed as desired with the movement of a very few cards, ordinarily not more than two cards in each column to be changed being moved in order to make room for a new card in the index.

I claim:

1. An index leaf provided with spaced rows of channels, and a plurality of card holders upon said index leaf, each card holder comprising a flexible metal strip having its end portions slidably engaged in said channels, and card retaining members carried by and extended around said flexible strip at each side of the vertical center thereof.

2. An index leaf provided with a plurality of spaced channels, and card holders slidably located in said channels, each card holder comprising a spring strip and a pair of spaced card retaining members having curved flanges extending around and located over opposite edges of the spring strip.

3. An index leaf provided with spaced rows

of channels, and a plurality of card holders upon said index leaf, each card holder comprising a flexible metal strip having its end portions slidably engaged in said channels, and card retaining members carried by said flexible strip at each side of the vertical center thereof, said card retaining members comprising channel strips extended and clamped around the flexible strip and spaced from the ends of the strip.

10 4. An index leaf provided with spaced rows of channels, and a plurality of card holders upon said index leaf, each card holder comprising a flexible metal strip having its end portions slidably engaged in said channels, and channel card retaining strips clamped around said flexible strip, said channel strips being spaced from each other whereby means may be inserted between adjacent card holders and under each card holder for removing a card holder from the index leaf channels.

15 5. A card holder including a flexible metal strip and spaced card retaining members carried by said flexible strip, said card retaining members comprising channel strips extended and clamped around said flexible strip.

20 In testimony that I claim the above, I have hereunto subscribed my name.

25 WILLIAM E. DUNNING.
